UNITED STATES PATENT OFFICE.

ERNEST C. OAKES, OF BLOOMFIELD, NEW JERSEY, ASSIGNOR, BY MESNE ASSIGNMENTS, TO EMPIRE MILKING MACHINE COMPANY, INC., OF ROCHESTER, NEW YORK, A CORPORATION OF NEW YORK.

VACUUM PUMP.

Application filed January 4, 1924. Serial No. 684,276.

This invention relates to vacuum pumps, and among its objects is the production of a design and construction of vacuum pump of improved efficiency, durability and greatly 5 avoiding the chance of wear or derangement of parts. In general it is aimed to provide a very simple construction, and one that in the hands of even unskilled attendants will function continuously and uniformly, and 10 provide in particular a reliable vacuum pump for such exacting requirements as in the case of providing a vacuum for the operation of milking machines.

In particular, the invention involves a 15 vacuum pump cylinder with no separate valves, with a plain piston having no valves, and effecting vacuum suction control by simple ports in a disc cooperating with the cylinder ports in a cooperating disc formed as 20 a simple integral part of the wall of the cylinder. The functioning is accomplished by rotating the vacuum pump cylinder around a middle axis transverse to the axis of the piston rod, and effecting this rotary motion 25 of the piston by means that affect in a very simple manner the reciprocation of the piston synchronously with the rotation of the port-control disc. By the particular construction an automatic means of lubrication 30 of the rotary disc port-control is assured in combination with the functioning of the pump, by the cooperation of the suction to maintain a very efficient contact for the port-control, as well as to assure the surface lub- 35 rication to prevent undue friction, both co-operating to assure automatically an ideal combination of pressure between discs con- 40 trolling the cooperation of cylinder ports and the vacuum line inlet as well as the ex- haust.

In the operation of this vacuum pump, the efficiency in the functioning by the co-operation of the various features of construction, has been found to greatly exceed 45 the efficiency of all of the other types of vacuum pumps which have heretofore been used to produce vacuum for similar purposes.

While various modifications may be made 50 and the design lends itself to constructions of various sizes, a particular embodiment involving the advantages is shown in the accompanying drawings, in which:

Fig. I is a vertical section on the axis of the driving and driven shafts, with the piston in middle vertical position. 55

Fig. II is a plan.

Fig. III is a view of the end embodying the vacuum line intake and the exhaust.

Fig. IV is a fragmentary section of the 60 cylinder and port connections, taken on the longitudinal axis of the cylinder with the piston in its middle position.

Fig. V is a section on the line 5—5, 65 Fig. IV.

The vacuum pump comprises a cylinder 1, piston 2 and piston rod 3. On one side of the piston a disc 4 has ports 5—5, respectively at each extreme end of the internal cylinder space. A shaft or stud 6 is formed 70 integral with the disc 4, and has its axis transverse to the cylinder midway between either end, so that the cylinder will turn around shaft 6 in substantially perfect balance. This shaft 6 is mounted on ball-bearings 7 and 8 supported in a housing 9 carried on bracket 10 substantially secured to a base 11. The shaft 6 is preferably held in the bearings by a stud screw 12, surrounding which is a cap 13 which encloses the 75 bearing space making it airtight, and through this cap and oil pipe 14 supplies oil from an oil-cup 15 which is preferably a drip oil supply, thereby automatically feeding slowly a measured amount of oil, which finds its 80 way to the surface to be lubricated, for reasons that will be later explained. 85

The piston rod 3 has an end bearing 16 engaged by a wrist-pin 17 mounted in a block 18 which is secured by suitable means, 90 such as screws 19—19, to the periphery of a shell 20, which may be termed the rotor, and which is preferably made out of a stamping in disc shape, with its hub secured to a flange 21, which in turn is rigidly secured to the end 22 of shaft 23 which is mounted in bearings 24—24 carried by bearing block 25 forming an integral part of the bracket or frame 26, which is securely held to the base 11 which is a common base with the bracket 100 10. The shaft 23 is shown as driven by a pulley 27, but gearing may be employed, or various modifications of drive may be applied to the shaft or to the shell or rotor 20. 105

The rotor shaft 23 is axially offset but parallel with the shaft 6 on which the piston

rotates, the offset being one-half of the total throw of the piston within the cylinder, so that with each complete rotation of the rotor shaft and casing 20, the cylinder turns on its transverse axis and the piston completes an out-and-in movement from one end of the cylinder to the other, and back, completing the cycle of operation of suction first through the ports at one end, and in the return stroke sucking through the ports at the other end, because synchronously with the movement of the piston the cylinder rotates on the axis of the shaft 6 bringing the ports 5 alternately in register with the vacuum line 28 whenever the piston is receding from the respective port 5. On the opposite side of the piston, the air being compressed is exhausted through the port 5 which the piston is approaching, and passes freely out of an outlet port in the face plate 29 formed as a part of the bearing-block 9, or fixedly secured thereto. The suction through the port 28 draws the air out of the vacuum line 30, which is connected with the piping of the vacuum system and thereby creates the desired vacuum throughout the system.

It will thus be noted that as the rotor revolves it drives the wrist-pin and the piston rod end thereby rotating the cylinder on the shaft 6, and synchronously moving the piston in the cylinder. The piston is arranged with a minimum possible clearance, and the piston rods are bushed with an airtight packing 31. Thus when the piston is at the limit of its stroke, as shown in Fig. I, all of the air has been expelled through the adjacent port 5 and through the clearance 29^a formed in the disc or plate 29. When the rotor has turned a few degrees in the direction shown by the arrow in Fig. III, the piston recedes creating suction from that end and in the adjacent port 5, and the port 5 then registers with the vacuum line port 28 establishing the suction connections with the vacuum line throughout the first half of the rotation of the rotor, and therefore during the entire suction stroke, but closing the port 5 connection at 28^a by the contact of disc 4 with the plate 29. That suction port is thus kept closed for about sixty degrees, and the return stroke of the piston begins to compress the air that has been sucked out of the vacuum line 30. As soon as this compression reaches a predetermined degree, the outlet space or recess 29^a in disc 29, is reached by the port 5, thereby establishing the outlet for the compressed air, and the exhaust continues during the remainder of the revolution, that is, until the piston has reached the return limit of its stroke when the exhaust connection of port 5 is closed as at 29^b. In the meantime a similar cycle has been performed on the other side of the piston, because of the other port 5 in sequence establishing connection with the vac-

uum port 28, cutting off, and then opening or registering with the exhaust gap 29^a in plate 29.

In the port-control view, Fig. V, is illustrated the successive positions of the ports 5-5 at opposite ends of the cylinder as a valve diagram in which said suction ports are shown in their relative positions wherein one of them *a* is closing for suction, while the other *b* at the piston end is closing the exhaust connection,—in position *a'* said port is closed by the disc contact, while *b'* position is opening register with the vacuum port,—when the one port is in position *a''* it is fully exhausting, and the port at the opposite end, in position *b''*, is in full suction registration, and so continues until the end of the stroke, while the opposite cylinder port remains open for exhaust until the piston reaches the end of the stroke. The lead of these ports while indicated as about twenty degrees' delay for opening of suction, and about sixty degrees' delay before exhaust opening, produces very efficient operation in the case of a pump having about 2½" diameter cylinder with 2¾" stroke and turning at about 300 revolutions per minute with variations of cylinder and variations of speed, it will be understood that the cylinder ports' relation to the suction port may be varied to secure the best efficiency, and the lead or lap may be varied, and likewise the size of the ports 5 may be varied, and would, in general, extend to a greater circular angle with increasing speed of pump, or would have their area otherwise suitably increased.

In particular it is to be noted that when the suction takes place tending to draw air out of the vacuum line 30, the suction also is effective throughout the joint between the piston plate or disc 4 and the port disc 29 thereby drawing these two contacting surfaces tight together and automatically assuring a close and airtight fit. However, with such suction drawing the discs together, there is also a tendency to create suction from the centre of the disc and from the bearings, so that any oil or lubricant located in the bearing space will be drawn into the space between the discs, thereby lubricating the discs automatically and generally in proportion to the pressure. In this way the suction, as well as the centrifugal forces affecting any oil that has passed from the bearings' space to the disc surface, will cause the oil to form a film between the disc surfaces thereby sealing them and making them airtight, so that nothing but oil will normally be drawn through such spaces, and the suction causing pressure between the discs will keep the film very thin, allowing only sufficient lubrication to form both an air-seal and also permit a small amount of oil to pass radially outward between the discs.

until the oil reaches the suction ports 5. When any oil reaches the ports 5, the suction will draw the oil into the cylinder, so that by this design of pump, the single oiling system also supplies any necessary lubrication in the interior of the cylinder where it spreads to the surface and is engaged by the piston and the piston rings, and provides all of the desired lubrication in order 10 to produce the maximum of efficiency of operation. By having the oil supply, such as oil-cup 15, of ample size to slowly feed oil through the end of the bearing space, the oil in small quantities passes through the bearings thereby supplying what is there needed, and by the suction and the centrifugal effect all needed oil is carried as above described, to the only wiping surface of the entire 15 pump, namely, the port-control engaging discs.

For the purpose of lubrication of the rotor shaft, an oil-cup 32 may be applied in the usual way, and the wrist-pin and piston rod end may be suitably lubricated in any 20 desired manner.

In order that the pump may be finished as a complete well-protected unit, a stamped disc 33 is formed and secured as by lag screws 34, to the fixed bracket 10, while the 25 peripheral flange 33^a of this casing carries over the rotor rim 20, with a small clearance, avoiding any friction, but still protecting the interior from the elements, as from water, dust and dirt.

It has been found that this construction of pump functions with great economy and produces a uniform suction and a steady vacuum, to any degree required for the purposes to which it is applicable. The construction throughout involves a minimum of parts and simplicity of parts, with no wearing surfaces affected by ordinary and regular operation, and therefore provides a 30 very durable as well as efficient pump.

While various modifications may be made without departing from the spirit of my invention, what I claim and desire to secure by Letters Patent is:

1. A vacuum pump comprising a power shaft, a cylinder with its axis at right angles to the power shaft, a shaft supporting the cylinder projecting at right angles thereto and parallel with and offset from the power shaft, a fixed support for said cylinder shaft having suction port and a discharge port, and a port disc associated therewith integral with the cylinder side and mounted to rotate in pressed contact with the support disc under the influence of the pump suction.

2. A vacuum pump comprising a power shaft, a cylinder at right angles thereto, a shaft supporting said cylinder at right angles and parallel to the power shaft offset from its axis, a fixed support for the cyl-

inder shaft having a port disc with ports 65 on opposite sides of its center and a vacuum line connection to said disc, and a cooperating port disc on the cylinder held in contact with the first disc by the vacuum action in the line. 70

3. A vacuum pump comprising a power shaft, a cylinder at right angles thereto, a shaft supporting said cylinder at right angles and parallel to the power shaft offset from its axis, a fixed support for and at one side 75 of the cylinder shaft having a port disc and a vacuum line connection to said disc, a cooperating port disc on the cylinder held in contact with the first disc by the vacuum action in the line, a bearing supporting said cylinder shaft, an airtight cavity enclosing said bearing having an oil inlet and a communicating passage with the space between the fixed and cylinder port discs. 80

4. A vacuum pump comprising a power 85 shaft, a pump cylinder at right angles thereto having a right angle shaft support, a piston rod projecting from said cylinder and a wrist pin therefor actuated by the power 90 shaft to revolve eccentrically with the cylinder support shaft, a fixed port disc surrounding the cylinder shaft and cooperating by suction contact with a rotating port disc on the cylinder. 95

5. A vacuum pump comprising a power shaft, a pump cylinder at right angles thereto having a right angle shaft support, a piston rod projecting from said cylinder and a wrist pin therefor actuated by the power 100 shaft to revolve eccentrically with the cylinder support shaft, a fixed port disc surrounding the cylinder shaft and cooperating by suction contact with a rotating port disc on the cylinder, a single piston on said rod having a throw throughout the entire 105 length of the piston space, and having a port at the limit of each piston end on one side through said cylinder port disc. 110

6. A vacuum pump comprising a power shaft, a cylinder at right angles thereto having a laterally-projecting shaft parallel to the power shaft but offset therefrom, a port disc on the cylinder at the opposite side of the cylinder from the power shaft and offset from the power shaft, a bearing for the 115 cylinder shaft and a fixed port disc thereon, means for holding the cylinder at its disc within predetermined clearance of the face of the fixed port disc.

7. A vacuum pump comprising a power shaft, a cylinder at right angles thereto having a laterally-projecting sole supporting shaft parallel to the power shaft but offset therefrom, a port disc on the cylinder, a bearing for the cylinder shaft and a fixed 120 port disc thereon, means for holding the cylinder at its disc within predetermined clearance of the face of the fixed port disc, and 125

an airtight chamber about the cylinder shaft bearing having its only outlet through the clearance between said discs.

8. A vacuum pump comprising a power shaft, a cylinder at right angles thereto having a laterally-projecting shaft parallel to the power shaft but offset therefrom, a port disc on the cylinder on one side extending uniformly toward each end of the cylinder, a bearing for the cylinder shaft and a fixed port disc thereon, means for holding the cylinder at its disc within predetermined clearance of the face of the fixed port disc, an airtight chamber around the bearings of the cylinder shaft, and an oil-supply feed to said airtight chamber whereby the suction drawing said discs together also draws a film of oil over their adjacent surfaces.

9. A vacuum pump comprising a power shaft, a pump cylinder at right angles thereto, a piston rod projecting from said cylinder and having a wrist pin connection with the power shaft, a lateral flange connected with said power shaft overhanging the plane of rotation of the cylinder and embodying a wrist pin bearing.

10. A vacuum pump comprising a power shaft, a pump cylinder at right angles thereto, a piston rod projecting from said cylinder and having a wrist pin connection with the power shaft, a lateral flange connected with said power shaft overhanging the plane of rotation of the cylinder and embodying a wrist pin bearing, and a fixed casing supported adjacent the fixed bearing of the pump cylinder shaft having its rim concentric with and in close proximity to the power shaft casing flange and forming therewith a protective joint.

11. A vacuum pump comprising a dished driving casing with an overhanging rim, a double-acting pump cylinder enclosed within said casing with an axis transverse thereto, a shaft supporting said pump cylinder at right angles to its axis, but disposed eccentrically to the drive casing axis, a bearing support for said cylinder shaft and a fixed port disc associated therewith and forming a lateral abutment for a contacting disc on the

side of the cylinder, suction ports in said cylinder disc at the extreme ends of the cylinder space, and a registering suction port in the fixed disc extending in an arc throughout slightly less than half the circumference.

12. A vacuum pump comprising a dished driving casing with an overhanging rim, a double-acting pump cylinder enclosed within said casing with an axis transverse thereto, a shaft supporting said pump cylinder at right angles to its axis but disposed eccentrically to the drive casing axis, a bearing support for said cylinder shaft and a fixed port disc associated therewith and forming a lateral abutment for a contacting disc at the extreme ends of the cylinder space, and a registering suction port in the fixed disc extending in an arc throughout slightly less than half the circumference, an exhaust gap in the fixed plate adapted to register with the port in the cylinder disc throughout an arc of rotation less than the arc of the suction port in the said fixed disc.

13. A vacuum pump comprising a dished driving casing with an overhanging rim, a double-acting pump cylinder enclosed within said casing with an axis transverse thereto, a shaft supporting said pump cylinder at right angles to its axis, but disposed eccentrically to the drive casing axis, a bearing support for said cylinder shaft and a fixed port disc associated therewith and forming a lateral abutment for a contacting disc on the side of the cylinder, suction ports in said cylinder disc at the extreme ends of the cylinder space, and a registering suction port in the fixed disc extending in an arc throughout slightly less than half the circumference, a fixed casing supported in conjunction with the bearings of the piston shaft, and having its periphery registering with the drive casing to form therewith a complete enclosing shell for the reciprocating parts of the vacuum pump.

In testimony whereof, I have signed my name to this application this 15th day of December, 1923.

ERNEST C. OAKES.
